UNITED STATES PATENT OFFICE

WALTER N. VANCE, OF CHICAGO HEIGHTS, ILLINOIS, ASSIGNOR, BY MESNE ASSIGNMENTS, TO LYON METAL PRODUCTS, INCORPORATED, OF AURORA, ILLINOIS, A CORPORATION OF ILLINOIS

FLOOR PLATE

Application filed March 22, 1928. Serial No. 263,936.

This invention relates to floor plates, and has more particularly reference to floor plates which are adapted for use in leveling articles of furniture, such as lockers and the like, which have angle iron legs.

It is the principal object of this invention to provide floor plates which may be readily built up into compact stack form.

Another object is to provide such floor plates which are adapted to be used in leveling up articles of furniture that have angle iron lugs, whereby the stacking lugs on the floor plates serve as holding lugs for the legs.

Numerous other objects and advantages of the invention will be apparent as it is better understood from the following description, which, taken in connection with the accompanying drawing, discloses a preferred embodiment thereof.

Referring now to the drawing,

Figure 1 is a plan view of a floor plate embodying my invention, dotted lines showing a possible setting of angle iron legs with respect to the lugs;

Fig. 2 is a side elevation of a built-up stack of such floor plates;

Fig. 3 is a cross-sectional view taken along the line 3—3 of Fig. 1, showing certain structural details; and

Fig. 4 is a view similar to Fig. 1, dotted lines showing the position of iron legs with respect to the lugs when two articles rest on the same plate.

Heretofore floor plates similar to that embodying my invention have been used but the lugs for holding the legs of furniture were of the same size or larger than the recesses produced in pressing the metal to provide the lugs. This caused difficulty in building up a stack if more than one plate was necessary.

A floor plate embodying my invention comprises a body 11 of sheet metal having holes 12 punched therethrough for the purpose of securing said plate to the floor and a plurality of projecting buttons or lugs 13 underneath

which are recesses 14. The lugs are preferably spaced about a central point in the plate in such a manner that they will engage and hold in position an angle iron leg resting upon said floor plate. An example of such a leg in position on a floor plate is shown in dotted lines in Fig. 1. By changing the position of the plate relative to the position of the angle irons, a double thickness of iron may be inserted between two adjacent lugs to accommodate two angle irons, whereby two articles may be supported upon the same plate.

It is to be noted that a lug 13 has a diameter smaller than that of the recess 14 beneath it, and that the depth of the recess is the same or slightly greater than the thickness of the lug, as shown in Fig. 3. This feature permits the stacking of the plates in such a way that a practically solid steady stack is obtained with no tendency of the individual members to shift or to lie at an angle to the others. Such lugs and recesses may readily be formed by embossing.

It is thought that this invention and many of its attendant advantages will be understood from the foregoing description, and it will be apparent that many changes may be made in the form, construction and arrangement of the parts without departing from the spirit and scope of the invention or sacrificing any of its material advantages, the form hereinbefore described being merely a preferred embodiment thereof.

I claim:

1. A metal floor plate adapted for use in leveling articles of furniture, comprising a substantially flat body, said body having a plurality of embossed lugs upon one face, said lugs being spaced apart along the arc of a circle, and a plurality of recesses on the other face, said recesses being immediately beneath said lugs and having interior dimensions greater than the exterior dimensions of said lugs, whereby said recesses on one plate are

adapted to receive and engage said lugs on another plate.

2. A floor plate adapted for use in leveling articles of furniture, comprising a substantially flat body, said body having a plurality of embossed lugs extending up from its upper face to engage the leg of an article of furniture being leveled, and having a plurality of recesses beneath said lugs of larger diameter than the diameter of said lugs, whereby said recesses of one plate are adapted to receive lugs on another plate.

WALTER N. VANCE.
